UNITED STATES PATENT OFFICE.

ANDREW J. BROOKINS, OF CHICAGO, ILLINOIS.

AUTOMATIC TRAIN-CONTROL APPARATUS.

1,384,552.

Specification of Letters Patent. Patented July 12, 1921.

Application filed April 24, 1920. Serial No. 376,355.

To all whom it may concern:

Be it known that I, ANDREW J. BROOKINS, a citizen of the United States, and a resident of Chicago, in the county of Cook and State 5 of Illinois, have invented certain new and useful Improvements in Automatic Train- Control Apparatus, of which the following is a specification, reference being had to the drawings accompanying and forming a part 10 hereof.

This invention relates to combined automatic and manually operable train carried apparatus adapted to co-act with members of track side installations of electric block 15 railroad systems.

Among the objects of this invention are to obtain a pneumatically and mechanically operable apparatus which is simple in construction, economically made, durable and 20 easily maintained in good working condition, and readily understood by men in charge thereof; to obtain an apparatus of the kind recited which is adapted to be controlled by an electroresponsive member 25 forming an element in the train carried portion of an electric circuit, the remaining elements of which are members in a track side installation; to obtain an apparatus provided with mechanically and manually 30 operable members which are adapted to co-act, and to co-act with members of said track side installation; and pneumatically operable members which communicate with the air supply of the air brake 35 system of the train and which are adapted to be operated by air under pressure supplied thereto by said air brake system. Additional objects are to obtain an apparatus whereof the pneumatically operable 40 mechanisms are adapted to establish communication between said air brake system and the atmosphere, thereby releasing air under pressure; and to obtain mechanism adapted to be manually operable to interrupt 45 said established communication upon the manual operation thereof, and an apparatus whereby, on the subsequent co-action of said pneumatically operable member and said members of the track side system said 50 manually operated member will be automatically returned to its normal position to permit the reestablishment of communication between the air brake system and the atmosphere. And a further object of this invention 55 is to obtain in the member thereof which

co-acts with track side members, a construction whereby upon the excessive wear thereof, means are provided to give warning to the men in charge of the apparatus.

An additional object is to obtain an apparatus of the kind named in which the use of a spring or springs is obviated, and close contact of a shoe on the descending side of a ramp is insured.

In the drawings the track side installations required are sufficiently identified and illustrated to render reference thereto in the description of the apparatus understandable, and the parts thereof directly co-acting with the train carried mechanisms are well 65 shown.

In said drawings Figure 1 is a side elevation of a ramp rail, a track rail, a truck on said track rail, and an apparatus embodying this invention operably mounted on said 70 truck.

Fig. 2 is a plan of track rails, showing in diagram trucks, or cabs, on said rails, and track side installations co-actuable with the apparatus embodying this invention.

Fig. 3 is a top plan view, partly in section, of said apparatus.

Fig. 4 is a side elevation, with a part thereof shown in vertical section.

Fig. 5, is a side elevation of the apparatus, 85 with the manually operable valve thereof shown in vertical section, a portion of the case being broken away to expose said valve and associated parts to view.

Fig. 6 is a similar view to Fig. 5, the shoe, 90 said valve, and associated parts, being in a different position.

Fig. 7 is a top plan view of said shoe; and

Fig. 8 a vertical section on line 8—8 of 95 Fig. 7, viewed in the direction indicated by arrows,

Fig. 9 is a transverse section of the manually operable valve, on line 9—9 of Fig. 3, viewed in the direction indicated by arrows, 100 and in the position illustrated in Fig. 5.

Fig. 10 is a similar view of said valve in the position illustrated in Fig. 6, (having been manually operated).

Fig. 11 is a similar view of said valve, in 105 the position illustrated in Figs. 4 and 5, the hub of the controlling lever being shown with said lever in "clear" position.

Fig. 12 is a side elevation of an element which is illustrated in Figs. 4, 5, and 6, as 110

mounted on the larger vertically movable plunger of the apparatus, showing a lever actuated thereby in end elevation.

Fig. 13 is an enlarged view of the head 5 of the plunger showing the arrangement of the packing more clearly.

A reference numeral applied to designate a given part indicates said part throughout the several figures of the drawings, wherever 10 the same appears.

Referring to Fig. 1, numerals 1 and 2 represent elements of an air under pressure supply pipe, which is in communication at its inlet end with the train air brake system 15 and at its outlet with the air receiving duct 9 of the apparatus. 3, 3, represent the frame of the truck on which the apparatus is illustrated as mounted, by supports 4, 4, 5, 5, represent insulating material between the 20 supports 4, 4, and the case of the apparatus. 6 represents the case of plunger 24, and 7 represents a removable cover to the case. 8 represents the case of the apparatus, and 9 an air duct. 10 represents an air chamber 25 in case 6, (see Figs. 4, 5, 6 and 10). 11 and 12, respectively represent air ducts or passage ways. 13 represents a passage way through the movable member of valve 39, said valve being hereinafter termed the per- 30 missive or manually operable valve. 14 represents a pneumatic signal, and 14¹ a communicating passage way between passage way 13 of the permissive valve and signal 14. 15 and 18, respectively, represent air 35 ducts or passage ways. 19 represents an inner plunger, and 17 an air retaining cup on the upper end of said plunger. 20 represents a retaining nut for the air retaining cup 22 of the large plunger, 24. 21 represents 40 an expanding ring in cup 22. Plunger 24 is vertically movable and is provided with chamber 16, in which chamber plunger 19 is vertically movable. 25 represents a collar which is rigidly secured on the upper portion 45 of plunger 24, as by nut and bolt 26 and 27. Plunger 24 is a two-part member, the lower part being cylindrical and the upper part forced thereinto. 25¹ represents a right angle arm, which is illustrated as 50 integral with collar 25, said collar forming the base of said arm. 28 represents a pivot which is secured in the lower end of arm 25¹, (see Fig. 12), and extends through a slot provided therefor in lever 29. By this 55 arrangement the upward and downward movement of plunger 24 moves lever 29 on its fulcrum, and when said lever is maintained in an elevated, or partially elevated position by notch 29² and latch 30, (see Fig. 60 4); said plunger is suspended by said lever. The fulcrum of lever 29 comprises hub 33 which is rigidly secured to shaft 34 by key 35, (see Fig. 3). The latch member 30 is fulcrumed on pin 30¹, and is arranged to 65 co-act with head 29¹ of lever 29, to be forced

by the raising of said lever into an inoperative position, as in Figs. 5 and 6, and engageable with notch 29², of said lever when turned on its fulcrum by lever 31¹, said lever 31¹ being actuated by the armature 32¹ 70 of the solenoid electromagnet 32. 32² and 32³, respectively represent conductors connecting the coil of electromagnet 32 to the case of the apparatus, from which case electric connection is established to the shoe of 75 the apparatus, and to box 3 of the truck, from which connection is made through the axle of the truck to the rail of the track. Shaft 34 is adapted to be manipulated to actuate valve 39. Said valve is illustrated 80 in horizontal section in Fig. 3, and in vertical section in Figs. 4, 5, 6, 9, 10 and 11. The smaller end of the valve 39 is provided with lugs, 38, 38, and the sides of the end of shaft 34 are removed to obtain a key end, 37, 85 which extends between said lugs 38, 38; and the larger end of said valve is squared to accommodate a wrench for the purpose of manually operating said valve, (see 40, Fig. 3). 41 represents the nut on stuffing box 90 41¹. 42, 42¹, represent the outside members of the movable mounted shoe of the apparatus, 43 the inner member of said shoe, and 43¹, a groove in said inner member. Said inner member consists of a horizontal base, 95 and vertical members 43² which are integral with said base. The outer sides of said vertical members flare outwardly as they ascend from said base, as is illustrated in Fig. 8, and designated by the numerals 43³, 43³. This 100 construction is to permit the said inner member to fall from the outer members, or to be forced therefrom by plunger 19, when by contact with ramp members 51, 53, the base of said inner member has been worn 105 through, thereby separating said vertical members. Members 42 and 42¹ are suspended by links 44, 44, from arms 44², 44². 45, 45, represent bolts through said links and through said outer shoe members; and 110 through said links and slots 44¹, 44¹. Said links 44, 44, also serve to hold outer members 42 and 42¹, together, against the outward thrust of sides 43³, 43³, of vertical portions 43² of base 43.

When said inner member falls or is forced from the outer members, the piston 19 is forced by gravity and air pressure on the upper side of cup 17, to a position below the inlet of duct 18, and thereupon communication is established between the train air brake system and the atmosphere, through conduit 1, 2, air passage way 9, chamber 10, duct 15, chamber 16, ducts 18, 11, 12, 13, 14¹, and signal 14, thereby sounding said 125 signal, and also automatically applying the brakes.

Valve 39 is adapted to control, in coaction with the plunger 24, the flow of air, under pressure, through the apparatus (see Figs. 130

4, 5, and 6). 46 represents the shell or case of valve 39. 47 represents a stuffing box on the upper end of plunger 24, and 48 a removable head to the upper end of shell 6. 5 49, (Figs. 4, 5, and 6), represents a stuffing box at the lower end of plunger 24.

50 represents a road side ramp, having sections 51, 53, which are electrically separated by insulating material 52, at the apex 10 thereof, (see Figs. 1 and 2). 54 represents a support which is positioned at the apex of the ramp, and is fastened to track rail 61. Additional supports, 55, 55, are fastened to the ties 56, 56.

15 In whichever direction a train is traveling the shoe of the apparatus comes in contact first with the ascending section, and as it rides up the section it raises the shoe and the plunger 24. In case the apparatus indicates "danger" the plunger is resting on said inner shoe, and is raised thereby to sound signal 14, as hereinbefore recited, and in case the plunger is suspended by latch 30 in notch 29², indicating "clear" the shoe 20 is raised by said ascending section until it is in contact with the lower end of said plunger and thereafter it raises said plunger, 25 to sound signal 14, as before.

In Fig. 2, 60 and 90, respectively represented a cab or truck, traveling in the direction indicated by arrow 90¹; section 51 is the ascending section, and 53 the descending section.

Referring to Fig. 1, the movable parts of 35 the apparatus being in their normal, or clear position, the operation is as follows; latch member 30 is in engagement with notch 29², and plunger 24 is suspended by lever 29. Cup 22 is in position to prevent the flow of 40 air from duct 9 to duct or conduit 12, and from thence through passage way 13 of valve 39, passage way 41¹ and signal 14; and cup 17 prevents the flow of air from conduit 15 to conduit 18. Conduit 15 being in direct 45 communication with conduit 9, (through chamber 10); and conduit 18 in communication with conduit 12, (through conduit 11), cup 17 is an additional element to prevent the flow of air under pressure from conduit 9 to conduit 12. Conduit 9 being in 50 communication with the air brake system of the train, (through conduits 2 and 1), and conduit 12 in communication with the atmosphere, (through passage way 13, conduit 14¹ and signal 14), the above named 55 cups, 17 and 22, while in said normal position, cut off communication between the air brake system and the atmosphere.

As the truck moves forward and block 60 43 of the shoe engages section 51 of the ramp, the shoe will be elevated as it ascends the ramp toward its apex, (central support 54,) thereby moving plunger 24, collar 25 on said plunger, and arm 25¹ up. Arm 25¹ 65 and lever 29 being connected by roller pin

28, said lever will also be moved up, turning on its fulcrum 34 and bringing face 29¹ into contact with latch 30, forcing said latch and lever 31 back, (see Fig. 5).

As the shoe nears apex 54 of the ramp, 70 plunger 24 is in position to register conduit 11 with conduits 9 and 12, thereby establishing communication between the train air brake system and the atmosphere, through conduits 1, 2, 9, 11, 12, valve passage way 75 13, conduit 14¹, and signal 14, sounding said signal. The said signal is sounded, as recited, every time the shoe passes over the apex of a ramp; but there will not be a sufficient volume of air released at said time 80 to cause an application of the brakes. As the shoe is ascending the ramp and moving plunger 24 up, cup 22 passes the outlet of conduit or duct 9, and the air admitted is compressed in chamber 10. Said compression of air in said chamber forces the movable parts of plunger 24 downward, as the shoe passes over the insulation 52 at the apex of the ramp, maintaining said shoe 85 in engagement with section 53 of the ramp, 90 said section regulating the downward movement of the shoe.

Should the signal indication be clear this section of the ramp is energized by the track side installation shown in diagram in Fig. 95 2, and the electromagnet 32, (see Fig. 3), will attract its armature 32¹ to move lever 31 on its fulcrum 31¹, said lever thereupon moving latch 30 in position to engage notch 29² of lever 29, (see Fig. 4), as soon as plunger 24 descends to register said notch and latch. The engagement of latch 30 with notch 29² prevents further downward movement of lever 29, and plunger 24 is suspended 100 on pivot 28, by member 25; and as the 105 shoe leaves the ramp the several parts of the apparatus are in the position they were before engagement therewith, (see Fig. 4).

A railroad electric block system adapted to energize the ramp hereinbefore referred to, 110 comprises duplicate units in each block, the unit in one of said blocks (block B), and some of the units in adjacent blocks, (A and C), are diagrammed in Fig. 2. The tracks in a block are separated from the tracks of 115 adjacent blocks by suitable insulation, (88). 81, 81, blocks A and B, respectively, represent a track battery; 82, 83, 85 and 87, respectively represent a conductor; (track rails 61 and 86 being also conductors). 84 120 represents a relay.

The above named elements in each block 125 form a track circuit which is the primary controlling element of all automatic signals and other devices to control train movements. Each block is usually equipped with a secondary or distant control, as battery 63, conductor 64, movable conductor 65, contact point 66, conductor 67, conductor 91, distant relay 92, conductors 93 and 62; all 130

indicated in Fig. 2. The track side installation of each block referred to, being the means of energizing section 53 of the ramp, consists of battery, or other source of electric energy, 63, conductor 64, movable conductor 65, contact point 66, conductor 67, movable conductor 68, contact point 69, conductor 70 to section 53.

Should the signal condition be otherwise than clear, as indicated in Fig. 2, the section 53 of the ramp will not be energized, therefore the magnet 32 will not attract armature 32¹, as the shoe is passing over said section in descending the ramp, and the lever 31 will not move latch 30 in position to engage notch 29²; and the plunger will move to its downward limit of travel, illustrated in Fig. 6, the valve 39, however, remains in its normal position, (illustrated in Figs. 4 and 5), until manually operated. When the plunger 24 is in said downward position, the cup 22 is in position establishing direct communication between conduit 9 and conduit 12, through chamber 10; and valve 39 being in the position illustrated in Figs. 4 and 5 thereby communication is established between the train air brake system and the atmosphere, as follows: conduits 1, 2, 9, chamber 10, conduits 12, 13, 14¹, and signal 14. The signal is sounded, and the continued release of air from the train air brake system will cause an automatic application of the brakes.

Said signal 14 will continue to sound until said valve 39 is manually operated, as by a wrench on end 40, and turned into the position in which it is illustrated in Fig. 6. Upon the raising of the plunger at the next ramp said valve is automatically turned from the position in which it is illustrated in Figs. 6 and 7 into its normal position in which it is illustrated in Figs. 4 and 5; by the automatic turning of plug 34, by means of end 37 being in the recess of end 38.

Referring to Fig. 2, for an explanation of the above operation, the apparatus is assumed to be mounted on the truck or cab 60, in block A, while the truck 90 is stationed in block C. It is old in the art to have the track circuit arranged so that the presence of a cab or truck in a block will cause the greater part of the electric current which is flowing from the source of electric energy for that block to flow through the wheels and axles of the said cab or truck. The coils of relay 84 of the track circuit will thereby be shunted, and there will not be a sufficient amount of electrical energy in them to cause the magnet thereof to attract its armature; said armature carrying movable conductor 65. While the armature is in attracted position said movable conductor 65 is in contact with contact point 66; but under the conditions last recited, said movable con-

ductor is not in contact with said contact point, and the track side installation of the distant or secondary control circuit is thereby opened at said contact point, and relay 92, of block B, is not energized, thereby causing the circuit of which the track side installation in block A, comprising members 61, 62, 63, 64, 65, 66, 67, 68, 69, 70 and ramp section 53 are elements, to be open, at contact point 69, and a stop operation of the cab or truck carried apparatus is obtained, as previously described.

After the train of which the cab or truck is a member has been brought to a stop the engineer, or other person in charge, by dismounting and fitting a wrench on the squared end of valve 39, can turn same to a closed position, thereby preventing a further escape of air from the train air brake system. The brakes can then be released and the train can proceed through said block. This is termed a permissive movement. When the shoe again ascends a ramp, as say, the ramp in the next block, said valve 39 is returned to its normal, (and open) position, by means of lugs 38, 38, being engaged by end 37 of shaft 34, as lever 29 is raised by the plunger 24. Assuming cab 90 remains in block C, the following operation occurs: When the shoe of the apparatus engages the ascending side of the ramp in block B, plunger 24 is moved upward carrying collar 25, arm 25¹, and lever 29 up, and shaft 34 is actuated; and end 37 of shaft 34 being in engagement with lugs 38, 38, turns the valve to open (and operative) position. Truck or cab 90 remaining in block C while the shoe of truck or cab 60 is in engagement with the descending side of said ramp in said block B, the circuit of the road side installation is opened at contact point 66 of relay 84 of block C; and magnet 32 of the apparatus on truck or cab 60 is not energized; hence plunger 24 moves to its lowest limit of travel, to force a stop operation of the apparatus in the same manner as hereinbefore described at the ramp in block A. To proceed the engineer must bring the train to a stop and again manipulate valve 39. Thus, while a permissive movement of the train is possible with cab 90 positioned within a prescribed number of blocks, it is necessary to come to a stop at each block and manually turn valve 39; said turning allowing movement of the truck or cab for one block only; valve 39 being automatically restored to operative position as the shoe travels up the ascending side of the ramp, as described. Should truck or cab 90 advance out of block C before the shoe on truck or cab 60 engages the descending side of the ramp in block A, a clear indication is given on the apparatus on truck or cab 60. The track circuits of blocks B

and C being closed thereby causes the secondary circuits to be in like condition, and magnet 32 to be energized.

End 37 of shaft 34, (see Fig. 9), does not engage lugs 38, 38, of valve 39 to turn said valve, so long as the apparatus is operated in proceed position; therefore said valve 39 remains in operative position, except when it is manually operated to close 10 communication between the train air brake system and the atmosphere, in what has been termed the permissive movement.

The pneumatic pressure in chamber 10, see Fig. 4, on cup 22 forces plunger 24, carrying plunger 19, against the base 43 of the shoe, when said shoe is in contact with a ramp, and obtains close contact of said shoe with the ramp, particularly with the descending side thereof. This effects good 20 electric connection between said shoe and said descending side of the ramp. The increased wear of said member 43 of the shoe caused thereby is immaterial, because of the provision, by the hereinbefore described construction of said member and the outer members 42, 42¹, of the shoe, which causes said member 43 to fall or be forced from the shoe when said base is worn through by said contact, when taken in connection with the 30 described means of giving warning concerning said member 43, and its leaving said outer members of the shoe. The foregoing construction of the shoe also provides for the breaking or disconnection of links 44, 35 44, from the supporting frame presented by arms 42², 44².

Lever 29 and plunger 24 are normally in "clear" position; and as at said time the plunger is suspended by the latch 30 being 40 in engagement with notch 29², the shoe is normally released from the pressure of said plunger thereon when said shoe first comes in contact with the ascending side of a ramp, and no shock is imparted to said shoe by 45 said first contact. After said contact is established, as the shoe rises on the ramp it takes its load off the plungers 24 and 19, without shock.

By referring to Fig. 6 it will be observed 50 that while a train is making a movement under danger indicated conditions, with the permissive valve closed the plunger 24 is resting on the shoe, with plunger 19 in the groove of the shoe, and movement will be 55 imparted to valve 39 toward open position, as soon as the shoe engages with the ramp.

By referring to Figs. 3, 5 and 9 it will be observed that as long as valve 39 remains 60 in open position, the end 37 of shaft 34 is free to move to and from in the different positions to which it is subjected by the normal operation of the apparatus without causing movement of said valve.

Train movements on a clear track are 65 usually made at normal speed. By referring

to Fig. 4 it will be observed that the plunger 24 is held suspended while a train which is equipped with this apparatus is in "clear" territory. Thus, when a shoe first engages a ramp, under normal conditions it will not be in engagement with plunger 24, therefore the shoe will not have to overcome the resistance of the pressure in chamber 10, to move the plunger until it is well in engagement with said ramp. This obviates shocks 75 and liability of breakage.

I claim:

1. In a train control apparatus provided with a chamber, an upwardly movable plunger, an upwardly movable shoe arranged to transmit upward movement thereof to said plunger, a duct communicating at its inlet with air under pressure in an air brake train system and at its outlet with said chamber, and said plunger arranged to control said outlet, in combination with a manually operable valve and a connection between said plunger and said valve arranged so that upward movement of said plunger controls an open position to said valve, and a duct communicating with said chamber and said valve.

2. In a train control apparatus, provided with a chamber, an upwardly movable plunger, an upwardly movable shoe arranged to transmit upward movement thereof to said plunger and on its downward movement to permit downward movement of said plunger, a duct communicating at its inlet with air under pressure in an air brake train system and at its outlet with said chamber, and said plunger arranged to control said outlet, in combination with a manually operable valve and a connection between said plunger and said valve arranged so that upward movement of said plunger controls an open position to said valve and downward movement of said plunger permits a closed position to said valve, means to manually close said valve, and a duct communicating with said chamber and said valve.

3. In a train control apparatus provided with a shell, a chamber in said shell, a movable plunger in said chamber, a movable shoe adapted to transmit movement to said plunger, means to suspend said shoe from said shell, said chamber having an inlet in communication with air under pressure in a train air brake system, said plunger adapted to retain said air under pressure in said chamber, in combination with an additional chamber having an inlet in communication with said first chamber and an outlet communicable with the atmosphere, and an additional movable plunger in said additional chamber, said movable shoe and said suspending means adapted to hold said additional plunger in position against said air under pressure in said additional chamber.

4. In a train control apparatus, a shell, a

chamber in said shell, a movable plunger in said chamber, a movable shoe adapted to transmit movement thereof in one direction to said plunger, a plurality of means to suspend said shoe from said shell, said chamber having an inlet in communication with the air under pressure of a train air brake system, said plunger adapted to retain said air under pressure in said chamber, in combination with an additional chamber provided with an outlet, said additional chamber in communication with said first chamber, an additional plunger in said additional chamber, and means to control the position of said plungers.

5. In a train control apparatus, a case, a chamber in said case, a movable plunger, a movable shoe arranged to transmit motion to said plunger, said chamber having an inlet in communication with air under pressure in a train air brake system and an outlet in communication with a signal and the atmosphere, said plunger adapted to control said outlet, in combination with an additional chamber in said movable plunger, said additional chamber having an inlet in communication with said first chamber and an outlet, an additional movable plunger in said additional chamber adapted to control 25 said last outlet, said shoe adapted to hold said additional plunger in position, against said air under pressure, to obstruct communication between the inlet and outlet of said additional chamber.

35. 6. In a train control apparatus, a case, a chamber in said case, a movable plunger in said chamber, a movable shoe arranged to transmit movement in one direction to said plunger, a plurality of means to suspend 40 said shoe from said case, said chamber provided with an inlet in communication with air under pressure in a train air brake system, and said plunger adapted to retain said air under pressure in said chamber, in combination with an additional chamber in communication with said first chamber and provided with an outlet, an additional plunger in said additional chamber normally obstructing said outlet therefrom, and said 45 shoe arranged to normally hold said additional plunger in normal position, whereby said shoe being in abnormal condition said additional plunger is moved, by said air under pressure in said additional chamber, 50 from said normal and obstructing position.

7. In a train control apparatus provided with a case, a chamber in said case, a movable plunger in said chamber, a movable shoe 55 arranged to transmit movement to said plunger in one direction, means to suspend said shoe from said case, said chamber provided with an inlet in communication with air under pressure in a train air brake system, 60 said movable plunger adapted to retain air

under pressure in said chamber, in combination with an additional chamber provided with an inlet in communication with said first chamber and an outlet communicable with the atmosphere, an additional movable plunger in said additional chamber adapted to obstruct said last outlet, said shoe arranged to be held by said suspending means against said air under pressure, to obstruct said outlet from said additional 75 chamber.

8. In a train control system, a track side member, in combination with a train carried apparatus having in combination as elements thereof, a case, a chamber in said case, a movable plunger in said chamber, a movable shoe adapted to engage with and be moved by said track side member and to transmit said movement to said plunger, a duct communicating at its inlet with air 80 under pressure in a train air brake system and at its outlet with said chamber, said plunger arranged to compress said air in said chamber on said movement thereof, to thereby cushion and yieldingly force said 85 plunger on to said track side member when in contact therewith.

9. In a train control system, a trackway, a road side installation at intervals along the trackway, a train pipe with air under pressure, said air being a controlling element of the train, a passage way communicating with said train pipe and communicable with the atmosphere, a movable member adapted to obstruct said passage way, said 90 air arranged to yieldingly force said member in a determined direction, a lever, a connection between said lever and said member, a latch adapted to engage said lever to limit the movement in said direction, a contact member arranged to co-act with said 100 roadside installation to move said member against said air under pressure, said lever, said connection and said member arranged to move said latch from said engaged position on the movement of said member by said contact member.

10. In a train control system, a trackway, a road side installation at intervals along the trackway, a train pipe under air pressure, said air being a controlling element of the train, a passage way communicating with said train pipe and communicable with the atmosphere, a movable member adapted to obstruct said passage way, a lever with 115 an engageable projection, a connection between said lever and said member, said member arranged to be moved in a determined direction by said air under pressure, a latch member adapted to engage said projection and an electro-responsive member adapted to co-act with said roadside installation, to move said latch member in engaging position, said latch, said lever and said connection arranged to retain said moy- 120 130

able member against said air pressure in position to obstruct said passage way.

11. In a train control system, a track side member, a train carried apparatus comprising a shell, a chamber in said shell, an upwardly movable plunger in said chamber, a duct on said plunger, a movable shoe adapted to engage said track side member, said shoe adapted to transmit movement thereof,

10 upon said engagement, to said plunger, a duct communicating at its inlet end with a source of air under pressure and at its outlet with said chamber, an additional duct communicable with a signal, said plunger,

After the first two years of the project, the first results were presented at the 18th International Congress of the International Society for Traumatic Stress Studies (ISTSS) in San Antonio, Texas, USA, in 2003. The results showed that the intervention was effective in reducing symptoms of PTSD and depression in the participants. The intervention was also found to be cost-effective, with a cost-benefit ratio of 1.25. The results were published in the *Journal of Traumatic Stress* (2004, 17, 111-118).

train pipe and a source of air under pressure supply, said air being a controlling element of said system, in combination, an apparatus provided with a passage way communicating with said air under pressure and communicable with the atmosphere, a movable member adapted to obstruct said passage way, a latch member adapted to retain said movable member in obstructing position, and an electroresponsive member adapted, when energized, to co-act with said roadside installations to move said latch member to retaining position.

19. In a train control system, a track side member provided with ascending and descending faces, in combination with a cab carried apparatus comprising a case, a chamber in said case, a movable plunger in said chamber, a movable shoe adapted to engage with and be moved by said track side member and to transmit said movement to said plunger, a duct communicating at its inlet with air under pressure in a train air brake system and at its outlet with said chamber, said plunger arranged to compress said air in said chamber on said movement thereof to thereby cushion and yieldingly force said plunger to said track side member when in contact therewith, an additional duct in communication with a pneumatic signal, a duct on said first plunger, said first plunger upon said movement arranged to obstruct communication between said first duct and said chamber, and said duct on said plunger adapted to establish communication between said first duct and said additional duct.

20. In a train control apparatus, a shoe consisting of a plurality of members, in combination with means to suspend said members, and a member supported by said plurality of members and arranged to co-act with a roadside member, said co-acting member arranged to separate from said shoe upon a determined wear of the contacting face thereof.

21. In a train control apparatus, a shoe consisting of a plurality of parts, in combination with means to movably suspend said shoe and a roadside member arranged to co-act with one of said parts, said co-acting part comprising a base and vertical members integral with said base, arranged to separate from the remainder of said shoe and from said base, on a determined wear thereof.

22. In a train control apparatus, a shoe comprising a plurality of outer parts and an inner part, in combination with means to movably suspend said outer parts, and a road side member arranged to co-act with said inner part, said means to suspend arranged to maintain said outer parts in their

assembled position, and said outer parts arranged to maintain said inner part in its 65 assembled position, and said inner part arranged to be subjected to wear by its contact with said co-acting road side member, and to separate into a plurality of members, and from said outer part, on a determined 70 wear thereof.

23. In a train control apparatus, a plunger, means to suspend said plunger midway of its limit of travel, means to move said plunger in one direction and means including a movable shoe to move it in the opposite direction, in combination with said movable shoe and a road side member arranged to co-act with said shoe to move said shoe in a determined direction, said shoe, plunger 80 and road side member related so that, said plunger being suspended, the initial movement of said shoe on its contact with said roadside member advances said shoe to said plunger, and additional movement of said 85 shoe moves said plunger along therewith.

24. In a train control apparatus provided with a passage way, a plurality of means to obstruct said passage way, said means comprising a normally open and manually operable member and an additional normally closed member, in combination with a shoe and a roadside member, all arranged to co-act, whereby said additional member being in an abnormal and open position, upon the 95 obstructing of said passage way by said manually operable member, the said co-action moves said additional member into normal and obstructing position, and moves said manually operable member from said 100 obstructing position.

25. In a train control apparatus provided with a passage way, a plurality of means to obstruct said passage way, said means comprising a manually operable 105 member and an additional member adapted to co-act therewith, said additional member arranged to control and normally maintain said manually operable member in open position with said passage way unobstructed, in combination with a shoe and a roadside member, all arranged to co-act, whereby said additional member being in an abnormal and open position, upon the obstructing of said passage way by said manually operable member, the said co-action moves said additional member into normal and obstructing position, and moves said 110 manually operable member from said obstructing position.

ANDREW J. BROOKINS.
